CENTRIFUGAL MACHINE

Arthur Underwood Ayres, Chestnut Hill, Pa., assignor to The Sharples Corporation, a corporation of Delaware

Application April 2, 1938, Serial No. 199,730

5 Claims. (Cl. 233—23)

This invention relates to improvements in high speed analytical centrifuges adapted to effect the rapid sedimentation of extremely small dispersed particles for the performance of analyses generally of the kind described in Svedberg and Nichols United States Patent No. 1,648,369.

The invention has been developed in connection with a machine for revolving a small sample of the substance to be studied transversely through a narrow beam of light at such high speed that a continual image of the illuminated sample is formed at the point of observation. Photographs of the rotating sample may be taken at intervals of time and at the termination of the treating period the photographs may be checked with a microphotometer for density against a known standard. In this way the amount of subsidence in each photograph can be determined and the rate of subsidence can be calculated.

In the centrifugal analysis of colloids, filterable viruses, and the like, it is necessary to rotate the substance under treatment at a sufficiently high rate of speed to generate the very high centrifugal forces necessary to cause sedimentation. It is also desirable to maintain a uniform temperature during the treatment, thus avoiding the convection currents which interfere with subsidence.

It is therefore an object of the present invention to provide a machine which will generate great centrifugal force with the application of minimum motive power. It is a further object of the invention to provide a machine of this type which will operate without the generation of any substantial amount of heat.

These objects are obtained through the use of improved bearing and drive mechanism and by adapting the machine for the maintenance of an unusually high vacuum during the operation thereof.

More specifically the invention contemplates the reduction of friction in the rotating parts by guiding the drive spindle in radial bearings of a special design and by supporting the entire weight of the rotating members on a thin film of air without any further thrust bearings, and to provide for the rotation of the substance under treatment under sub-atmospheric conditions.

It is a further object of the invention to provide a centrifugal machine which is capable of high speed operation without generating vibrational forces which would otherwise interfere with successful operation of the machine. To the end that vibration at high rotational speeds

may be minimized, the invention utilizes a flexible rotor shaft which is rotated in resiliently mounted bearings.

Further objects and advantages of the invention will become apparent as the description thereof proceeds in light of the drawings forming a part of this application. In the drawings, like reference numerals indicate like parts throughout the several figures, and

Figure 1 is a vertical sectional view taken through a high speed centrifugal machine embodying the features of the invention; and

Figure 2 is an enlarged vertical sectional view more particularly illustrating the bearing and drive structure with associated parts.

The centrifugal machine illustrated in the drawings comprises a body member A providing a rotor casing and an oil collecting chamber, and a head member B providing rotor drive mechanism and an oil reservoir.

The body member A is of relatively heavy nickel steel construction and has formed centrally therein a chamber 10 adapted to house a centrifugal rotor during operation of the machine. The chamber 10 is formed by the side wall, the bottom, and by overhanging lip portion 11 at the top thereof. In the base of the body member is an oil collecting chamber 12 having an oil drain outlet 14 normally closed by a closure plug 16. Near the top of the body is a drip cup 18 which communicates with the oil collecting chamber 12 through a vertical passage 20 in the side wall. The body member A is provided in its bottom with a through passage 22, the inner end of which is closed by a glass or quartz plate 24. Through the side of the body is a port 26 adapted for connection with a vacuum pump.

The body member A may be supported on a suitable base 28 having therein a transverse passage 30 which is in communication with the through passage 22 of the body. In the transverse base passage 30 and located immediately under the through body passage 22 is a mirror 32, the angular position of which may be adjusted through a rod 34 and a thumb wheel 56. The adjusted position of the mirror 32 may be maintained by a set screw 38 which engages the rod 34.

The head member B is provided with a passage 40 in which are housed bearing and drive mechanism for a relatively flexible rotor spindle 42 which is connected to a rotor 44. At one side of the passage 40 is an oil reservoir 46 from which communication for oil under pressure is

provided to the rotating parts of the drive and bearing mechanism and from which oil may be drained by removing a drain plug 47. A bracket 48 extends upwardly from the top of the head B 5 and a transversely extending arm 49 thereof is adapted to support a bearing housing. In the transversely extending arm 49 is a bearing housing 50 which is threaded at its upper end into the arm 49. Intermediate the ends of the bearing housing 50 is a radial fin 52 which maintains the housing in proper location, and serves the more important function of a pivot which permits oscillation of the lower end of the housing 50. The space between the housing 50 and the depending portion 54 of the transversely extending arm 49 is sealed by means of a flexible member 56 which is held in place by a cap nut 58. The upper end of the bearing supporting bracket is suitably closed by means of a closure screw 59. 10 20 15 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330

A second bearing housing 62 is located in the passage 40 for positioning two spaced bearing sleeves providing support to the rotor spindle at spaced points towards its lower end. A spindle bearing sleeve 68 is fixed snugly in the upper end of the bearing housing 62 while a second spindle bearing sleeve 70 is fixed in snug engagement with the lower end of the bearing housing 62. The bearing housing 62 is located in spaced relation to the walls of the passage 40, and the space between it and the walls of the passage 40 is sealed by means of mounting and packing rings 64 and 66. These mounting and packing rings, as well as the ring 56, are constructed of relatively resilient and oil resisting composition.

The sealing function of the resilient rings 56, 40 64 and 66, is however, no more important than their function as resilient mountings for the bearing housings 50, 62. A relatively rigid motor shaft mounted in unyielding bearings would set up severe vibrational disturbances at very high 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330

Intermediate the lower end of the bearing housing 50 and the upper end of the bearing housing 62 is located the drive mechanism for the rotor spindle. This mechanism consists of an air motor or turbine 72 which is suitably fastened in driving relation to the spindle 42.

A body of non-vaporizable oil is normally maintained in the oil chamber 46 to a height above an oil duct 74 in the wall of the passage 40. The head B is connected with a source of air pressure through a suitable connection 76. Air under pressure is led from the inlet 76 through suitable pressure reducing valves and pressure gauges 77, and such air under pressure, for example five pounds per square inch, passes through a duct 78 to the oil chamber 46. Air under pressure, for example fifteen pounds per square inch, is led through suitable ducts formed in the head B (not shown) to an annular passage 80 surrounding a turbine housing 84 from which the same is discharged through tangential passages or jets 82 in the turbine housing against the face of the turbine wheel 72.

Air under pressure from the oil chamber 46 passes through an air passage 160 to the space

below the turbine wheel 72 with sufficient force to raise the wheel and the other rotating parts carried thereby from contact with a surface 86 against which the wheel 72 rests while the machine is not in operation. In this manner the thrust of all of the rotating parts is supported by the film of air escaping between the turbine wheel 72 and the underlying wheel support 86. The turbine wheel support 86 may be molded of suitable yielding plastic composition and the same rests on a yielding annulus 87 with which it forms an effective cushion into which the part 86 will be pressed by the air pressure.

During the operation of the machine oil under pressure in the chamber 46 is forced through the oil conduit 88 and passes around the bearing housing 50 and into the bearing housing through apertures 90 in the wall thereof. As a consequence of the pressure on the oil around the bearing housing 50, the resilient ring 56 is effectively deformed to prevent the passage of oil from the lower end of the supporting bracket. Consequently, the oil is compelled to seek escape through the very small space between the rotor spindle 42 and the bearing sleeve 60, thus providing continuous lubrication.

The oil that escapes from the bearing sleeve 60 falls on a deflector 91 which prevents its passage to the turbine and directs it into a drip pan 92 which surrounds the same. Excessive amounts of oil pass through an overflow pipe 96 which discharges into a suitable container.

The oil under pressure which surrounds the bearing housing 62 deforms the resilient rings 64 and 66 into contact with adjacent surfaces to seal the rotor chamber against leakage. It will be noted that the turbine wheel housing 84 is provided with a downwardly projecting lip 98 which lies against the upper packing ring 64, while at the lower end of the bearing housing 62 an oil catch 100 has an inwardly extending flange 102 which the lower ring abuts.

The oil under pressure from chamber 46 communicates with the passage 40 through the apertures 74 and 75, and with the interior of the bearing housing through apertures 104 formed therein. Any oil escaping from the bearing housing 62 must do so by passing between the bearing sleeves 70 and 68 and the spindle 42, thus insuring constant lubrication of the bearing surface and at the same time forming an effective seal for the rotor chamber. A deflector 106 attached to the spindle 42 prevents oil which escapes from the lower end of the lower bearing assembly from passing along the spindle into the rotor chamber. The deflecting plate 106 discharges oil into the oil collector 100 from which it flows to the oil cup 18 and to the oil collecting chamber 12 in the base of the machine. The oil which escapes through the bearing sleeve 68 passes through a passage 94 in the turbine housing 84 and is discharged through the overflow pipe 96.

The above described construction provides a bearing means which embodies a maximum amount of flexibility which is essential for high speed operation, while at the same time the widely spaced bearings maintain the mechanism in proper alignment. The small amount of clearance between the rotor spindle and its bearings permits the oil between these parts to form effective seals so that no air can enter the rotor chamber past the bearings.

A further feature of the invention resides in the means for adjusting the height of the bearing

60 above the turbine wheel 72 to offset nodes which might result in vibration. The upper end of the bearing housing 50 is provided with screw threads 108 which are adapted to engage threads 5 110 formed in the upper end of the bearing bracket 48. The vertical height of the bearing 60 can be altered merely by turning the housing 50 to adjust its position in the bracket 48.

The rotor 44 is provided with a cell carrying 10 passage 110 which is adapted to receive a cell composed of an outer casing 112 and an inner casing 114 both of which are held against rotation by a pin 116 which extends therethrough and into a socket in the rotor. The cell 112 is also 15 provided with two glass or quartz discs 118 spaced from each other by a spacing member 120 to provide therebetween a space for a small sample of substance to be treated. An annulus 122 having a pin 124 resting in a slot formed in the cell 112 to prevent relative rotation is fixed by a locking ring 126 threaded into the rotor. The rotor 44 20 is cut away at points opposite the cell passage 110 as at 128 and 130 to provide proper balance.

The rotor, which is preferably constructed of 25 aluminum or an aluminum alloy, is fixed to its drive shaft 42 by means of a split collet 132. The lower end of the collet engages a shoulder 134 formed on the lower end of the shaft 42 to lock the two parts securely. A set screw 136 is provided in the upper end of the collet to engage 30 the shaft 42 in order to prevent shaft whip. The rotor is interchangeable with others of the same or of different design.

When the head B is properly located on the 35 body A, the space therebetween is sealed by means of a gasket 138. The optical system for observing the sedimentation in a sample of substance under treatment is completed by an adjustable mirror 140 which is carried on a mirror shaft 142, journaled for rotation in the head member. The mirror 140 may be adjusted to any desired angular position by manipulation of a thumb wheel 144 and the adjusted position of the mirror may be secured through a set screw 40 45 146 which engages the mirror shaft 142. The base plate of the head B has formed therein an aperture 148 which is closed by a glass or quartz plate 150. The passage 22 in the body and the passage 148 in the head are in alignment and 50 include the vertical planes through which the rotor cell must pass during its rotation. As a consequence, light reflected by the mirror 32 is caused to pass through the rotating cell and the constant image of the substance under treatment 55 in the cell is reflected by the mirror 140 for observation by an attendant or for photographic purposes as hereinbefore suggested. The chamber 152 which houses the mirror 140 is normally closed by a removable plate 154.

60 In a typical operation of the machine a sample to be studied is placed in the cell of the rotor and the rotor is first operated at a speed of approximately 10,000 R. P. M. as the vacuum within the rotor chamber is being brought to approximately .2 micron, after which the rotational speed is increased to 80,000 R. P. M. to develop a maximum centrifugal force of 250,000 times gravity. Under these conditions the temperature rise in the sample under treatment does not exceed 2° 65

70 C. during the course of a four-hour treatment. The use of vacuum enables the rotor to turn five times as fast without increasing the driving power, and more important, the vacuum avoids local heating from air friction. During high 75 speed operation, a shaft of light is directed

through the rotating cell and photographs are taken at intervals of time, and at the termination of the treating period the photographs are compared as hereinabove suggested.

The construction of the driving mechanism and the rotor spindle bearings permits high speed rotation with a minimum amount of driving power. Furthermore, the flexibility of the drive spindle and its support in the resiliently mounted bearings, as hereinabove described, permits high speed 10 operation with the generation of a minimum amount of frictional heat, and is of such construction that vibrational forces are most adequately absorbed. The suppression of vibration is of particular importance in the practice of 15 analytical processes which involve photographing the sample under treatment. Should vibration occur in the device during the photographic operation, a blurred image would be recorded and precise results in the analysis of the photograph 20 would be precluded. The machine is self-contained and requires a minimum amount of skill and attention for its successful operation.

While hereinabove a single embodiment of the invention has been illustrated it is obvious that 25 extensive modifications in the construction may be made without departing from the spirit of the invention as defined in the subjoined claims.

I claim:

1. In a head for a centrifugal machine having 30 a flexible spindle and a rotor secured thereto adapted for rotation at high speeds, the combination comprising a rotor spindle passage through said head, a bearing sleeve in said passage, resilient means for securing said sleeve 35 in said passage for radially yieldable movement, axially spaced spindle bearings mounted in said sleeve, a drive motor connected to said spindle at a point opposite said bearings from the zone of securement of the rotor spindle to the rotor, 40 a bearing for said spindle located along said spindle at a point beyond said motor, a bearing housing for said last-mentioned bearing, means for supporting said housing, a resilient mounting interposed between said housing and said supporting means to permit radially yieldable movement of said housing, and fluid means for supporting the spindle and rotor during rotation thereof.

2. In a head for a centrifugal machine having 50 a flexible spindle and a rotor secured thereto adapted for rotation at high speeds, the combination comprising a rotor spindle passage through said head, a bearing sleeve in said passage, resilient means for securing said sleeve 55 in said passage for radially yieldable movement, spindle bearings mounted in said sleeve, a drive motor connected to said spindle at a point opposite said bearings from the zone of securement of the rotor spindle to the rotor, a bearing for said 60 spindle located along said spindle at a point beyond said motor, a bearing housing for said last-mentioned bearing, means for supporting said housing, a resilient mounting member interposed between said housing and said supporting means 65 to permit radially yieldable movement of said housing, means for adjusting said housing longitudinally of said spindle, and fluid means for supporting the spindle and rotor during rotation thereof.

3. In a head for a centrifugal machine having a flexible spindle and a rotor secured thereto adapted for rotation at high speeds, the combination comprising a rotor spindle passage through said head, a bearing sleeve in said passage, co- 70 75

- operating means between the sleeve and the walls of the passage to form a seat for a resilient mounting member, a resilient and deformable mounting member interposed between said sleeve and the walls of said passage at the extremities thereof for securing said sleeve for radially yieldable movement and for sealing the space between said sleeve and said passage walls, axially spaced spindle bearings mounted in said sleeve,
- 10 a drive motor connected to said spindle at a point opposite said bearings from the zone of securement of the rotor spindle to the rotor, an oil reservoir in said head, means affording communication from said reservoir to said passage and said sleeve, and means for placing said oil under pressure whereby a lubricant may be provided to said bearings and said resilient and deformable member are urged into sealing contact with adjacent surfaces.
- 20 4. In a head for a centrifugal machine having an axially movable flexible spindle and a rotor secured thereto adapted for rotation at high speeds, the combination comprising a rotor spindle passage through said head, a bearing sleeve in said passage, resilient means interposed between said sleeve and the walls of said passage for securing said sleeve for radially yieldable movement, axially spaced spindle bearings mounted in said sleeve, a drive motor connected to said spindle at a point opposite said bearings from the zone of securement of the rotor spindle to the rotor, an oil reservoir in said head, means for admitting air under pressure to said reservoir,
- 25
- 30

oil passages affording communication from said reservoir to said passage and said sleeve for lubricating said spindle bearings, and means for admitting air from said reservoir to a space directly under said motor for axially moving said spindle.

5. In a head for a centrifugal machine having an axially movable flexible spindle and a rotor secured thereto adapted for rotation at high speeds, the combination comprising a rotor spindle passage through said head, a bearing sleeve in said passage, resilient means for securing said sleeve in said passage for radially yieldable movement, spindle bearings mounted in said sleeve, a drive motor secured to said spindle at 15 a point opposite said bearings from the zone of securement of the rotor spindle to the rotor, a bearing for said spindle located along said spindle at a point beyond said motor, a bearing housing for said last-mentioned bearing, means 20 for supporting said housing, a resilient mounting interposed between said housing and said supporting means to permit radially yieldable movement of said housing, an oil reservoir in said head, means affording communication between said reservoir and all of the said bearings, means for admitting air under pressure to said reservoir, and means for admitting air from said reservoir to a space directly under said motor for axially moving said spindle. 30

ARTHUR UNDERWOOD AYRES.
